ARTICLE OF FLATWARE

Clayton A. Laughlin, Minneapolis, Minn., assignor to Arthur Salm Inc., Chicago, Ill.

Filed May 12, 1969, Ser. No. 17,123

Term of patent 14 years

Int. Cl. D7—03

U.S. Cl. D54—12

FIG. 1.

FIG. 2

FIG. 3

FIG. 4

FIG. 5

FIG. 6.

FIG. 7.

FIG. 8.

FIG. 9.

FIG. 10.

FIG. 11.

FIG. 1 is a front elevation of an article of flatware showing my new design as embodied in a salad fork;

FIG. 2 is a fragmentary front elevation of the handle of an article of flatware showing the distinguishing features of my design;

FIG. 3 is a fragmentary left side elevation of the handle portion shown in FIG. 2;

FIG. 4 is a fragmentary rear elevation of the handle portion shown in FIG. 2;

FIG. 5 is an enlarged section taken on line 5—5 of FIG. 2;

FIG. 6 is an enlarged section taken on line 6—6 of FIG. 2;

FIG. 7 is an enlarged section taken on line 7—7 of FIG. 2;

FIG. 8 is an enlarged section taken on line 8—8 of FIG. 2;

FIG. 9 is a perspective view of an article of flatware showing my design as embodied in a serving spoon;

FIG. 10 is a perspective view of an article of flatware showing my design as embodied in a knife; and

FIG. 11 is a perspective view of an article of flatware showing my design as embodied in a carving fork.

I claim:

The ornamental design for an article of flatware, substantially as shown and described.
